UNITED STATES PATENT OFFICE.

ARTHUR L. EDWARDS, OF MAUPIN, OREGON.

DRILLING MACHINE.

1,424,997.

Specification of Letters Patent. Patented Aug. 8, 1922.

Application filed July 25, 1921. Serial No. 487,257.

To all whom it may concern:

Be it known that I, ARTHUR L. EDWARDS, a citizen of the United States, and resident of Maupin, in the county of Wasco and State 5 of Oregon, have invented certain new and useful Improvements in Drilling Machines, of which the following is a specification.

This invention relates to improvements in drilling machines and more particularly to 10 the power transmitting means therefor.

Briefly stated, an important object of this invention is to provide a pitman rod or power transmitting mechanism for a drilling machine having novel means to relieve the 15 machine of excessive and destructive strain due to the sticking of the drilling mechanism in the hole.

A further object is to provide a pitman rod which by reason of its strain relieving qualities permits of the use of a continuous cable. 20

A further object is to provide a pitman rod for drilling machines which may be efficiently applied to various types and styles of drilling machines and which is comparatively 25 cheap to manufacture.

Other objects and advantages of the invention will be apparent during the course of the following description.

In the accompanying drawings forming 30 a part of this application and in which like numerals are employed to designate like parts throughout the same,

Figure 1 is a side elevation of the improved pitman rod applied to a drilling machine of the walking beam type.

Figure 2 is a side elevation of the improved pitman rod applied to a slightly different type of drilling machine.

Figure 3 is a side elevation of the improved pitman rod in its inoperative position.

Figure 4 is a central vertical longitudinal sectional view through the improved pitman rod in its inoperative position.

Figure 5 is a central vertical longitudinal sectional view through the improved pitman rod in its extended or operative position.

Figure 6 is a horizontal sectional view taken on line 6—6 of Figure 4.

Figure 7 is a perspective of a yoke embodied in the invention.

Figure 8 is a perspective of a sleeve embodied in the invention.

Figure 9 is a fragmentary perspective of the locking arm embodied in the invention. 55

In the drawings wherein for the purpose of illustration is shown a preferred embodiment of the invention, 10 designates a power wheel driven by any suitable means and having a crank 11 to which the improved pitman 60 rod 12 is pivotally connected. As illustrated in Figure 1, the upper portion of the pitman rod which forms the subject matter of this application is connected to a walking beam 13 in any desired or well known 65 manner.

The pitman rod 12 may be connected to a variety of types of machines and by way of illustration the same has been shown in Figure 2 as applied to a drilling machine 70 having cranks 15 and 16 employed as a means for transmitting power to the drilling mechanism.

The improved pitman rod or power transmitting device generally designated by the 75 numeral 12 is particularly designed to relieve the drilling mechanism of the severe strains encountered when the drilling mechanism is suddenly stopped through striking an obstruction. 80

Specifically, the improved pitman rod comprises a tubular body 20 which slidably and freely receives a plunger 21. As illustrated in Figure 4 a sleeve nut 22 is threaded into the lower end of the tubular body 20 85 and forms an abutment for a retractile coiled spring 23. The coiled spring 23 which surrounds the plunger 21 engages an annular shoulder 24 formed at the lower end of the sleeve 26. The sleeve 26 which is slidable on the plunger has its upper portion reduced in its external diameter to define an annular shoulder 27 which contacts with a second retractile coiled spring 28. The second retractile coiled spring 28 is also arranged on 90 the plunger 21 and is confined between the sleeve 26 and an annular enlargement or shoulder 30 formed adjacent the upper end of the plunger. 95

The plunger is formed beyond the integral shoulder 30 with a threaded shank 31 to which a U-shaped yoke generally designated 100

by the numeral 32 is connected. The U-shaped yoke is formed with a connecting portion having an opening 34 which freely receives the threaded shank 31. The yoke 32 which is provided with arms 35 on opposite sides of the plunger is held in an adjusted position by means of lock nuts 36 threaded on the shank 31 on opposite sides of the connecting portion of the yoke. By 10 adjusting the nuts 36 the yoke 32 may be adjusted longitudinally of the plunger for a purpose to be fully hereinafter described.

The means for holding the plunger in a set position with relation to the tubular body under normal conditions includes a 15 pair of oppositely arranged arms 40 pivotally connected at their upper ends to the pairs of laterally projecting apertured ears 41 by means of pivot pins 42. The lower 20 terminal portions of the arms 40 are formed with inwardly directed fingers 44 curved transversely and received within an annular groove 45 formed in the intermediate portion of the sleeve 26. When the inwardly 25 directed fingers 44 are yieldably held in the annular groove or recess 45, the sleeve is detachably held in a set position with the result that the plunger 21 is held in a set position with relation to the tubular body.

30 When the transversely curved fingers 44 are received within the annular recess 45 the ends of the fingers contact with the annular shoulder constituting the side walls of the annular recess so that the endwise movement 35 of the sleeve is prevented. In order to move the plunger 21 for a substantial distance with relation to the tubular body it is necessary to move the arms 40 outwardly against the pressure of a pair of coiled 40 springs 46 which are secured to the hooked terminal portions of laterally projecting extensions 47 formed adjacent the forward ends of the arms 40.

The arms 40 may be moved outwardly to 45 the position illustrated in Figure 5 by moving the yoke 32 longitudinally and thereby forcing the beveled ends 49 of the same between the forward portions of the arms and sides of the sleeve 26.

50 When an excessive longitudinal strain on the pitman rod is encountered a pull downwardly is exerted on the plunger 21 which results in the retractile coiled spring being compressed to a limited extent so as to move the beveled ends 49 between the sleeve 26 and transversely curved inner sides 50 of the arms. With the arms 35 of the yoke thus wedged between the sleeve and the curved portions 50 of the arms 40, the fingers 44 55 are released from engagement with the shoulders constituting the walls of the annular recess 45.

With the fingers 44 released from the annular recess 45 strain on the pitman rod is 60 transmitted to the coil spring 23 whereby 65

the crank may complete its stroke. However, when the tool within the well is released from the obstruction the coil spring 23 returns the sleeve to its original position on the plunger so that the fingers 44 70 may re-enter the annular recess 45. Therefore, when the strain is relieved, the pitman rod automatically returns to its operative position for the resumption of the drilling operation. 75

The yoke 32 may be positioned with its end 49 close to the inwardly directed terminal portions of the arms 40 so as to cause the arms 40 to spread as soon as the strain becomes slightly excessive. On the other 80 hand the yoke 32 may be positioned adjacent the rear end of the threaded shank 31 so that the plunger will have to move quite a distance before the beveled ends 49 are wedged between the inwardly directed portions of the arms 40. When the yoke 32 is thus positioned the spring 28 is permitted to partially contract before the arms 40 are spread. This adjustment of the pitman 85 rod renders the same less sensitive to strains. 90 A cushioning and tightening spring 54 is mounted on the plunger adjacent the nut 22 and may be adjusted by means of nuts 56 threaded on the lower terminal portion of the plunger 21. 95

By way of illustration I have shown the terminal portion of the plunger 21 equipped with a U-shaped attaching member 58 which may be attached to a link 60 or the like which is in turn connected to the crank of 100 the drilling machine. However, the improved pitman rod may be connected to the drilling machine in a variety of ways as is obvious. The tubular body may be connected to the machine by means of the extension 105 62 having apertures 63 for the reception of fastening devices.

With reference to the foregoing description taken in connection with the accompanying drawings, it will be apparent that 110 a pitman rod constructed in accordance with this invention will relieve the drilling mechanism of excessive strain and will resume its normal position when the strain is overcome. 115

Having thus fully described my invention what I claim as new and desire to secure by Letters Patent is:—

1. A pitman rod comprising a body, locking arms carried thereby and having fingers, 120 a plunger in said body, a sleeve slidable on said plunger, a coiled spring confined between said sleeve and one end of said plunger, a second coiled spring confined between said sleeve and one end of said body, said sleeve being provided with means engaging the fingers of said locking arms whereby to hold the sleeve in a set position, and an attaching means carried by said body. 125

2. A pitman rod comprising a body, lock- 130

ing arms carried thereby and having fingers, a plunger in said body, a sleeve slidable on said plunger, a spring confined between said sleeve and one end of said plunger, a second 5 spring confined between said sleeve and one end of said body, said sleeve provided with means engaging the fingers of said locking arms whereby to hold the sleeve in a set position, and means urging the arms into locking engagement with said sleeve.

3. A pitman rod comprising a body, locking arms carried thereby and having fingers, a plunger in said body, a sleeve slidable on said plunger, a spring confined between said 15 sleeve and one end of said plunger, a second spring confined between said sleeve and one end of said body, said sleeve provided with means engaging the fingers of said locking arms whereby to hold the sleeve in a set position, and coiled springs arranged on opposite sides of said body and connected to 20 said arms for urging the same into locking engagement with said sleeve.

4. A pitman comprising a body, a plunger extending into the body, a sleeve slidable on 25 said plunger, a coiled spring confined between said sleeve and the upper portion of said plunger, locking means engaging said sleeve to detachably hold the same in position, and a yoke secured on said plunger for 30 releasing said locking means.

5. A pitman comprising a body, a plunger extending into the body, a sleeve slidable on said plunger, a spring confined between said 35 sleeve and the upper portion of said plunger, locking means engaging said sleeve to detachably hold the same in position, a yoke secured on said plunger for releasing said locking means, and a second spring confined 40 between said sleeve and one end of said body.

6. A pitman comprising a body, a plunger extending into the body, a sleeve on said 45 plunger, a spring confined between said sleeve and the upper portion of said plunger, locking means engaging said sleeve, a yoke secured on said plunger for releasing said locking means, a second spring confined between said sleeve and one end of said body, 50 and a cushioning spring mounted on said plunger.

7. A pitman comprising a body, a plunger extending into the body, a sleeve slidable on 55 said plunger, a coiled spring confined between said sleeve and the upper portion of said plunger, locking means engaging said sleeve to detachably hold the same in an adjusted position, a yoke secured on said plunger for releasing said locking means, a 60 second spring confined between said sleeve and one end of said body, and a cushioning spring mounted on said plunger adjacent one end of said body, said yoke being adjustable on said plunger.

65 8. A pitman comprising a tubular body,

a plunger extending into the tubular body and having a shoulder adjacent one end, a sleeve slidable on said plunger and having an annular recess, locking arms pivotally connected to said body and having fingers adapted to be received within said annular recess, a U-shaped yoke secured on said plunger and having arms arranged between said first named arms and said sleeve, the terminal portions of said second named 75 arms being beveled and adapted to separate said arms and said sleeves, and a coiled spring confined between said shoulder and the sleeves.

9. A pitman comprising a tubular body, 80 a plunger extending into the tubular body and having a shoulder, a sleeve slidable on said plunger and having an annular recess, locking arms pivotally connected to said body and having fingers adapted to be received within said annular recess, a U-shaped yoke secured on said plunger and having arms arranged between said first 85 named arms and said sleeve, the terminal portions of said second named arms being beveled and adapted to separate said arms and said sleeves, and a spring confined between said sleeve and one end of said body.

10. A pitman comprising a tubular body, 90 a plunger extending into the tubular body and having a shoulder adjacent one end, a sleeve slidable on said plunger and having a recess, locking arms pivotally connected to said body and having inwardly directed fingers adapted to be received within said 100 recess, a U-shaped yoke secured on said plunger and having arms arranged between said first named arms and said sleeve, the terminal portions of said second named arms being beveled and adapted to separate 105 said arms and said sleeves, a spring confined between said sleeve and one end of said body, and means urging said arm into locking engagement with said sleeve.

11. A pitman rod comprising a body, a 110 plunger associated with said body, a locking arm carried by said body, and a yoke carried by said plunger and adapted for releasing said locking arm.

12. A pitman rod comprising a body, a 115 plunger associated with said body, a locking arm carried by said body, a yoke carried by said plunger and adapted for releasing said locking arm, and means yieldably urging said locking arm to an operative 120 position.

13. A pitman rod comprising a body, a 125 plunger associated with the body, a sleeve slidable on the plunger, a locking arm carried by the body and having means engaging said sleeve, and a releasing device for removing said locking arm from engagement with said sleeve.

14. A pitman rod comprising a body, a plunger associated with the body, a sleeve 130

slidable on the plunger, a locking arm carried by the body and having means engaging said sleeve, a releasing device for removing said locking arm from engagement with said sleeve, and springs engaged with opposite sides of said sleeve.

15. A pitman rod consisting of a pair of

sections, a sleeve slidable on one of the sections, a locking arm carried by the other section and adapted for engaging said sleeve, and a yoke carried by one of said sections and having means for releasing said arm from engagement with said sleeve.

ARTHUR L. EDWARDS.
